UNITED STATES PATENT OFFICE.

ISHAM RANDOLPH, OF CHICAGO, ILLINOIS.

COMBINED RAILWAY-SWITCH AND SIGNAL-OPERATING MECHANISM.

SPECIFICATION forming part of Letters Patent No. 441,378, dated November 25, 1890.

Application filed April 29, 1890. Serial No. 349,942. (No model.)

To all whom it may concern:

Be it known that I, ISHAM RANDOLPH, a citizen of the United States, residing at Chicago, in the county of Cook and State of Illinois, have invented a new and useful Improvement 5 in a Combined Railway-Switch and Signal-Operating Mechanism, of which the following is a specification.

My invention relates to an improvement in 10 the class of mechanism for operating simultaneously from a distant location (as the ordinary switch-operator's cabin through the medium of a suitable lever system,) a railway-switch and semaphore; and my object is 15 to provide simple and reliably-operative mechanism for the purpose, but which shall serve effectively to lock and maintain locked the switch in a position to which it has been thrown until the semaphore shall have been 20 first adjusted to display the signal for the opposite throw of the switch.

I prefer to provide my combined switch-operating semaphore and switch-locking improvement with further precautionary mechanism 25 for operating a detector-bar, so combining the last-named mechanism with the other as to cause the latter to be operated therewith; but I do not wish to be understood as limiting my improved combination to the 30 inclusion of the detector-bar appliance nor, essentially, to a particular form of the switch-operating appliance.

In the accompanying drawings, Figure 1 is a broken plan view showing my improvement 35 as including all the features mentioned; Fig. 2, a similar view showing the details of a detector-bar device; Fig. 3, a section taken on the line 3 of Fig. 2 and viewed in the direction of the arrow; Fig. 4, a view in broken 40 front elevation of a dwarf semaphore; Fig. 5, a view of the same in broken side elevation, the side presented being that nearest the upper edge of the longer side of the sheet containing Fig. 1; Fig. 6, a broken view, in elevation, of the dwarf semaphore, presenting 45 the opposite side thereof from that shown in Fig. 5; and Fig. 7, a view similar to that presented in Fig. 6, but showing the interlocking dog and bell-crank mechanism in their 50 relative positions of locking the semaphore-arm at its "danger" position.

A is a switch-operating appliance, preferably (though not necessarily) of the construction set forth in Letters Patent of the United No. 410,332, granted me on the 3d day of 55 September, 1889. It comprises, generally described, a longitudinally-movable bar r , confined between guides on a base r' and connected, through the medium of the links q , each pivoted to the other at one end and at 60 such end to the bar r , with opposite ends of a centrally-pivoted bar p on the base, the ends of the links q where they are connected with the bar p being longitudinally slotted, as shown, a bar p' , slotted longitudinally near 65 its opposite ends and there pinned through the slots to the bar p , on which it is supported, to extend lengthwise thereof, and a switch-connecting bar o , pivotally connected with the bar p by the pin, which connects a link q 70 therewith. The bar p' is designed to be connected from one end by a wire, cable, or the like p^2 , with an operating-lever, (not shown, but which may be located in the operator's cabin, as is common,) and from its opposite 75 end through a wire, cable, or the like p^3 , passing around a guide-pulley X , (and containing links or other mechanism hereinafter described,) with the said lever.

B is a detector-bar appliance, preferably 80 (but not necessarily) involving the construction set forth in my pending application for Letters Patent of the United States, Serial No. 340,792, filed on the 17th day of February, 1890, and comprising the following details: 85 A base n , supporting a lever m , extending across and pivoted to it and provided with stops n' and m' at opposite extremities of its expanded end, to be engaged by a tongue l , projecting horizontally from one edge of a 90 bar k , having recesses k' and k^2 at opposite sides of the tongue, the bar being confined on the base to extend across the lever m and movable longitudinally in guides, and a detector-bar device C , (which may be of a well-known construction and need not, therefore, be described in detail,) having the detector-bar i , supported on toggle-links t and connected, through a link i' , a horizontal pivotal cross-head i^2 , and a link i^3 , with an end of the 95 lever m .

D is the signal, (preferably in the form

of a so-called "dwarf semaphore,") involving the following-described construction of parts on a vertical post h , provided with a pivotal signal-arm h' and lamp h^2 , which latter may be arranged to signal through a suitable lens h^3 on the rear end of the semaphore-arm: At one side of the base of the post h is pivoted a bell-crank g , one arm of which is connected, as in the manner shown, through the medium of a link g' , with the arm h' , the other arm extending into the path of a bar g^2 at an offset g^3 , provided therein, the bar being supported in horizontal position on the side of the base of the post h between guides x to enable it to be moved longitudinally, and connected from one end by the wire p^3 with the device A, (or to the bar p' through the medium of the appliance B, as shown, if provided,) and from its opposite end by the wire p^3 or the like passed around the pulley X with an operating-lever. (Already referred to as not shown.) The longitudinal movement of the bar g^2 should be limited by stops v on the base of the semaphore-post (and which are indicated by dotted lines in Fig. 5) in the path of the lateral abutments at the bases of the eyes v' on the ends of the bar, and at which the cable p^3 is secured to it.

On the side of the semaphore-post h opposite that provided with the bell-crank g is pivotally supported another lever, preferably, also, substantially in the form shown, of a bell-crank f , engaged toward one end by a dog f' on the same axis as the bell-crank g , and having pivotally connected with its opposite end a link f^2 , extended into proximity with the switch-bar o , and there pivotally connected with one end of a suitably-fulcrumed bell-crank e , having pivoted to its opposite end one end of a bar o' , connecting the bell-crank e with the switch-rail (not shown) near its free end, the connecting-bar o , which is similarly joined to the switch-rail, extending thus parallel with the bar o' .

With my improvement applied with all the devices described the operation is as follows: Operating a lever to exert strain on the connecting medium p^2 in the direction indicated by the arrow d pulls the bar p' of the device A in that direction, but without immediately moving the switch-bar o , owing to lost motion due to the slots in the ends of the bar p' and links q . The operation also draws the bar k of the device B, and through it raises and lowers the detector i , provided the track be clear, and if it be obstructed by a train that fact will be indicated to the operator by the resistance encountered by him at the lever produced by the obstruction to the detector-bar preventing continued movement of the bars k and r , which obviously prevents throwing of the switch. If, however, the track be clear, so that the devices A and B may be operated, the strain will also be exerted on the bar g^2 to draw it at its offset g^3 against the bell-crank g in its path, and thereby, through the link g' , raise the signal-arm h' to the dan-

ger position. The turning of the axis of the bell-crank g also turns the dog f' thereon at the opposite side of the base of the post h to disengage it from the bell-crank f . Then the bar r is free to be moved by the continued strain on the bar p' and effects the desired throw of the switch, since it has been released from the locking effect of the bar o' by permitting the latter to be moved with the movement of the switch-bar o , (which in throwing the switch causes the latter to exert force against the bell-crank e through the locking-bar o' ,) owing to the release of the dog f' from the bell-crank f . Thus the lost motion due to the slots (about one and three-quarter inch each) in the ends of the bar p' and to those (about three-quarters of an inch each) in the ends of the toggle-links q of the device A serves before affecting the switch to permit the detector-bar appliance (if employed) to perform its function and operates the semaphore and unlocks the switch at the bell-crank f with the setting of the semaphore to "danger" to permit throwing of the switch only after the appropriate semaphore-signal has been displayed, the locking effect of the switch in the position from which it has been thrown being accomplished by the relative positions assumed by the dog f' and bell-crank f , (illustrated in Fig. 6,) while in their positions illustrated in Fig. 7 they lock the semaphore-arm at "danger," leaving the switch free to be thrown. The reverse operation of the appliances by appropriately operating the lever to exert the proper strain on the wire p^3 is of course owing to the same provision for affording the lost motion described, also to cause the detector-bar appliance to perform its function and to throw the switch and withdraw the bar g^2 controlling the semaphore, so as to permit the arm h' to drop to its normal safety position, and thereby also to return the dog f' to the position illustrated in Fig. 6, thereby reproducing its engagement with the bell-crank f to lock the switch.

The details at the semaphore-post for setting the semaphore, and thereby effecting the unlocking of the bar o' and resultant locking of the semaphore and the unlocking of the bar o' , may be variously modified without thereby departing from my invention. Hence I do not wish to confine my improvement to the exact means for the purpose shown and described, though they are believed best to accomplish the desired object.

What I claim as new, and desire to secure by Letters Patent, is—

1. In combination with a railway-switch-operating appliance connected with the switch by a connecting-bar o as the switch-throwing medium, a semaphore D, a rod o' , connected at one end directly with the switch to one side of the connection therewith of the rod o , locking mechanism, substantially as described, at the semaphore-post for locking the sema-

5 phone-signal at its danger position, and locking mechanism, substantially as described, at the semaphore-post connected with the said signal-locking mechanism and with the rod o' and adapted to operate by unlocking the signal to lock the switch and to operate by locking the signal to unlock the switch, substantially as set forth.

2. In combination with a railway-switch-operating appliance in which the throwing of the switch is accomplished through the medium of a connecting-bar o , a semaphore D, a lever g , connected with the semaphore-arm h' by a link g' , a longitudinally-reciprocating bar g^2 , connected with the switch-operating appliance and engaging with the said lever, a dog f' on the axis of the lever g , a lever f , engaged by the dog, and a locking-rod o' , for connection at one end with the switch and connected from its opposite end with the lever f through intermediate mechanism actuated by longitudinal movement of the rod o' to turn the lever f , substantially as and for the purpose set forth.

25 3. In combination with a railway-switch-operating appliance in which the throwing of the switch is accomplished through the medium of a connecting-bar o , a semaphore D, a bell-crank g , pivotally supported on the semaphore and having one arm connected by a link g' with the signal-arm h' , a longitudinally-reciprocating bar g^2 , connected with the switch-operating appliance and engaging at an offset g^3 with the other arm of the said bell-crank, a dog f' on the axis of the bell-crank g , a bell-crank f , engaged toward one end by the dog and connected from its opposite end by a link f^2 with one arm of a bell-crank e , and a locking-rod o' , for connection at one end with the switch and connected at its opposite end with the other arm of the bell-crank e , substantially as and for the purpose set forth.

4. In combination, a switch-operating appliance A, having a longitudinally-reciprocating bar r on its base and surmounted by a bar p' , confined thereon through slots near its opposite ends and connected by pivotal links q with a pivotal lever p at opposite sides of its pivot through slots in the ends of the links, and a switch-connecting bar o , connected with the lever p , a semaphore D, a lever g , connected with the semaphore-arm h' by a link g' , a longitudinally-reciprocating bar g^2 , connected with the bar p' and engaging with the lever g , a dog j'' on the axis of the lever g , a

lever f , engaged by the dog, and a locking-rod o' , adjacent to the bar o , for connection at one end with the switch and connected from its opposite end with the lever f through intermediate mechanism actuated by longitudinal movement of the rod o' to turn the lever f , substantially as and for the purpose set forth. 60

5. In combination, a switch-operating appliance A having a longitudinally-reciprocating bar r on its base and surmounted by a bar p' , confined thereon through slots near its opposite ends and connected by pivotal links q with a pivotal lever p at opposite sides of its pivot through slots in the ends of the links and a switch-connecting bar o , connected with the lever p , a semaphore D, a bell-crank g , pivotally supported on the semaphore and having one arm connected by a link g' with the signal-arm h' , a longitudinally-reciprocating bar g^2 , connected with the bar p' and engaging at an offset g^3 , provided in it, with the other arm of the bell-crank g , a dog f' on the axis of the said bell-crank, a bell-crank f , engaged toward one end by the dog and connected from its opposite end by a link f^2 with one arm of a bell-crank e , and a locking-rod o' , for connection at one end with the switch and connected at its opposite end with the other arm of the bell-crank e , substantially as and for the purpose set forth.

6. In combination, the switch-operating appliance A, for controlling a switch through the medium of a connecting-bar o , the appliance B, connected with and controlling the detector-bar device C, a semaphore D, having a lever g , supported on one side of its post near the base and connected with the semaphore-arm h' by a link g' , a longitudinally-reciprocating bar g^2 , connected through the appliance B with the bar p' of the appliance A and engaging with the lever g , a dog f' on the axis of the lever g at the opposite side of the semaphore-post, a lever f , engaged by the dog, and a locking-rod o' , for connection at one end with the switch and connected from its opposite end with the lever f through intermediate mechanism actuated by longitudinal movement of the rod o' to turn the lever f , substantially as and for the purpose set forth. 90 95 100 105

ISHAM RANDOLPH.
